UNITED STATES PATENT OFFICE.

HOWARD D. VOGT, OF SAGINAW, MICHIGAN.

SIGN.

Application filed September 14, 1923. Serial No. 662,679.

To all whom it may concern:

Be it known that I, HOWARD D. VOGT, a citizen of the United States, residing at Saginaw, in the county of Saginaw and 5 State of Michigan, have invented new and useful Improvements in Signs, of which the following is a specification.

This invention relates to signs and has for its object the provision of a novel sign 10 structure which may be called self illuminating inasmuch as it is designed for use along road ways, at corners and crossings, at railroad crossings, upon the tail boards of trucks, vehicles and the like, or at any other 15 location where it will receive light from the lamps of approaching automobiles, the light being reflected by the sign to indicate danger or to mean any other signal, the sign being moreover so formed that any 20 legends, symbols or the like thereon will stand out very prominently and conspicuously.

With the above and other objects and advantages in view the invention consists 25 in the details of construction to be herein-after more fully-described and claimed and illustrated in the accompanying drawings, in which:

Figure 1 is a front elevation of a sign 30 constructed in accordance with my invention,

Figure 2 is a section therethrough on the line 2—2 of Figure 1,

Figure 3 is a detail section on the line 35 3—3 of Figure 2,

Figure 4 is a fragmentary elevation showing a modified form,

Figure 5 is a section therethrough on the line 5—5 of Figure 4,

Figure 6 is a rear elevation of another 40 form,

Figure 7 is a similar view of a still different modification,

Figure 8 is a detail section showing another 45 modification,

Figure 9 is a fragmentary view of another form.

Referring more particularly to the drawings and especially Figures 1 to 3, I have 50 shown the sign as formed from a sheet or pane 10 of glass or other transparent material having one surface 11 plane and having its front surface ribbed as shown at 12 so as to have a somewhat prismatic shape. 55 This glass might be of any desired color throughout and red is convenient though

somewhat over worked and might therefore result in some mishap on account of confusing it with a tail lamp or warning lantern at an excavation. The back of the 60 glass, that is the plane side 11 is coated with a silver backing 13 to produce a mirror effect which will insure reflection of any light thrown upon the front of the sign. This device may of course bear any desired 65 legend or symbol depending upon the purpose for which the sign is used. In the present instance I have shown an arrow and the word "Detour" though this is simply an example of the possibilities. To make 70 this reading matter stand out prominently, some mode of treatment must be used on the back ground and in the present instance I have shown in these three figures the silver backing as omitted as indicated at 14 75 to define the symbol and the legend.

In the use of this form it is quite apparent that if the sign be located along the road at any desired point where the rays from vehicle lamps may strike upon it, such light 80 will be reflected and make the sign very conspicuous, the legend and symbol thereon standing out prominently in black.

Instead of the face of the glass pane being formed with the alternate ridges and 85 grooves of a sharp nature, I may prefer that this face be molded to define a plurality of knob like projections 15 arranged in staggered relation as shown in Figures 4 and 5. In this instance the treatment to define the 90 legend and symbol may be the same as above described though it is apparent that some other means may be resorted to.

In Figure 6 I have illustrated the sign as consisting of a glass pane or plate 16 of 95 some solid color but smooth on both sides, the rear side being coated with the silver backing as above described with the backing scraped away or omitted to define the reading matter.

In Figure 7 I have shown the glass pane or plate 17 as having both sides smooth with the letters 18 of the legend silvered on the back of the sheet.

Figure 8 shows the glass pane or sheet 105 19 as having the letters 20 of the legend molded with ribs or corrugations, the backs of the letters being silvered as shown at 21 and the spaces between and around the letters, or the remaining area, being of any 110 preferred solid color as shown at 22.

In Figure 9 I have shown the back of

- the sheet 23 as painted black or some other dark color in such a way as to define the letters 24 of the sign or this back ground might be frosted and the letters shown in 5 red or any other contrasting color. In fact the possibilities as to coloring, backing with reflecting material, frosting and ribbing the front surface are somewhat unlimited and there is no limitation in respect thereto.
- 10 While I have shown and described the preferred embodiments of the invention it is of course to be understood that I reserve the right to make such changes in the form, construction and arrangement of parts as will not depart from the spirit of the invention or the scope of the subjoined claim. 15
- Having thus described my invention I claim:
- A sign formed from a sheet of transparent material having its rear side plane and 20 coated with a backing of light reflecting material, the backing being omitted along certain areas to define legends which will be non-reflective, the front of the glass being formed with a refractive surface only in 25 front of the letters forming the legend.
- In testimony whereof I affix my signature.

HOWARD D. VOGT.
